AUTOGRAPHIC REGISTERS

Allen B. Cooke, Danville, Ill.

Application August 4, 1958, Serial No. 752,714

10 Claims. (Cl. 282—16)

The present invention relates to autographic registers, and is particularly concerned with improvements in the autographic registers covered by my prior patent on autographic registers, No. 2,743,944, issued May 1, 1956.

One of the objects of the invention is the provision of an improved autographic register, the structure of which is more simple than the devices of the prior art, and which permits the installation of the tickets used in the register with greater ease and facility by reason of the fact that one of the rollers is carried by the upper cover, which is movably mounted so that the rollers and gears are adapted to be separated for this purpose.

Another object of the invention is the provision of an improved autographic register of the type in which the rollers may be separated, having special provision for maintaining the timing of the gears when they are brought together again by the closure of the cover, movably supporting the upper roller and its gears.

Another object of the invention is the provision of an improved autographic register which is simpler in construction, which includes a minimum number of parts, which may be manufactured at a lower cost, and which is adapted to be operated more efficiently and with less possibility of trouble than any of the devices of the prior art.

Another object of the invention is the provision of improved means for securing the gears of the two rollers in proper position for re-engagement so that the rollers, which bear cams for feeding the paper tickets, are in proper relation to each other when they are re-engaged after opening the cover for the insertion of tickets or for other purposes.

Another object of the invention is the provision of an improved autographic register which is adapted to be used for filing the top original ticket and dispensing one or more lower tickets to the customer, and which may be adapted to be modified slightly for dispensing the top ticket and filing the lower tickets.

Another object of the invention is the provision of an improved autographic register in which the tickets are torn off against the feed roller, thereby eliminating the necessity for a tear-off edge, and in which the feed rollers are mounted for resilient pressure toward each other into engagement with the paper tickets.

Another object of the invention is the provision of improved latching means for securing the cover, which cannot be latched until both sides of the cover are moved down into proper position, thereby insuring uniform pressure on both ends of the feed rollers and on both sets of feed discs and cams.

Another object of the invention is the provision of an improved autographic register structure which is adapted to be employed with tickets that are already provided with carbons or with carbons so located that the tickets slide over fixed carbons or which may be employed with copying sheets of the type having a chemical on the back that unites with pressure on the chemical on the front of the next sheet, thereby making copies.

2

Another object of the invention is the provision of improved ticket and copy sheet assemblies in which the chemicals are carried by separate sheets so that the tickets do not carry these abrasive coatings and the punches and shears that are used on the tickets are not damaged by abrasive chemical coatings now used on some types of tickets.

Other objects and advantages of the invention will be apparent from the following description and the accompanying drawings, in which similar characters of reference indicate similar parts throughout the several views.

Referring to the five sheets of drawings accompanying the specification;

Fig. 1 is a top plan view of an autographic register embodying the invention;

Fig. 2 is a side elevational view of the register of Fig. 1;

Fig. 3 is a sectional view, taken on the plane of the line 3—3 of Fig. 1, looking in the direction of the arrows, in a register of the type of Fig. 2, which dispenses top tickets and files lower tickets;

Fig. 4 is a sectional view, taken on the plane of the line 4—4 of Fig. 1, showing a modified form of register which files the top tickets and dispenses lower tickets;

Fig. 5 is a side elevational view of the register of Fig. 4;

Fig. 6 is a fragmentary sectional view, taken on the plane of the line 6—6 of Fig. 1, looking in the direction of the arrows;

Fig. 7 is a fragmentary sectional view, taken on the plane of the line 7—7 of Fig. 2, looking in the direction of the arrows;

Fig. 8 is a view in perspective of a directing guide used for directing lower tickets downward;

Fig. 9 is a similar view of a modified form of guide;

Fig. 10 is a fragmentary sectional view, taken on the plane of the line 10—10 of Fig. 6, looking in the direction of the arrows;

Fig. 11 is a fragmentary sectional view, taken on the plane of the line 11—11 of Fig. 6, looking in the direction of the arrows;

Fig. 12 is a fragmentary sectional view, taken on the plane of the line 12—12 of Fig. 4, looking in the direction of the arrows;

Fig. 13 is a fragmentary sectional view, taken on the plane of the line 13—13 of Fig. 6, looking in the direction of the arrows;

Fig. 14 is a fragmentary sectional view, taken on the plane of the line 14—14 of Fig. 6, looking in the direction of the arrows, with the synchronizing pawl in proper position for registry of the gears;

Fig. 15 is a similar view showing the pawl automatically withdrawn by closure of the cover;

Fig. 16 is a fragmentary sectional view, taken on the plane of the line 16—16 of Fig. 15, looking in the direction of the arrows.

Referring to Figs. 1-3, the present autograph registers are preferably enclosed in a casing 20 having a sheet metal bottom wall 21, which is bent upwardly at both of its sides to provide sheet metal side walls 22 and 23 of substantially rectangular form, but slightly tapered toward the top.

The bottom wall 21 carries a pair of pivoted end wall members 24 and 25, each of which is pivoted to the bottom wall by means of a sheet metal hinge 26 and 27 and welded to the bottom wall 21 and to the end walls 24 and 25 and provided with pintles 28, 29.

The end cover member 25 extends upwardly to form the end wall 30 and has a horizontal portion 31 which terminates at 32 in Fig. 3, in the bottom filing and top dispensing type of machine.

In the top filing and bottom dispensing type of machine

of Fig. 4 the end wall member 25a has an upwardly turned portion 33 which terminates at 34 beneath the box-like portion 35 of the end cover member 24a of Fig. 4.

The end cover members 24 or 24a both have the end wall portions 36 and the elongated top wall portions 37, the top wall being in each case provided with a rectangular window 38 for exposing the ticket upon which the record is to be made. The elongated top wall 37 in each case has a box-like portion 35 for enclosing the feed rollers and having an upwardly extending wall 39, a horizontal portion 40, and a downwardly extending wall 41.

The cover member 25 is preferably provided with a tumbler barrel lock 42, the barrel of which carries a rotating locking bolt 43 for engaging a keeper 44 carried by the side walls. Keeper 44 comprises a channelled bar having flanges 45 at its ends welded to the side walls.

Thus the housing is locked at its left end in Fig. 3 to prevent unauthorized access to the used tickets which bear records; but the other cover member 24 need not be locked. The cover member 24 or 24a is provided with latching means adapted to be controlled by a finger lever 46 (Fig. 4) which projects upwardly through an aperture in the box-like portion 35.

This finger lever is pivotally mounted on the downwardly extending wall portion 41 of the box 35 by means of a bracket 47 having a flange 48 spot welded to the wall portion 41 and having a U-shaped flange 49 with a through pin 50 for pivoting the lever 46. The lever 46 is pivotally connected by means of hook shaped ends 51, 52 to a pair of wire connecting rods 53, 54, each of which has its other hook shaped end pivotally connected at 55 and 56 to the latching plungers 57, 58.

The box-like formation 35 in each case (Fig. 6) carries the bearing blocks 59, 60, which have guide sleeves 61, 62 for guiding the plungers 57 and 58, which serve as latching bolts. Plungers 57, 58 slide in cylindrical bores 63, 64 and have tapered rounded ends 65, 66 for guiding the plungers into round apertures in the keeper plates 67, 68 fixedly mounted on the side walls 22 and 23, inside the box-like portion 35.

The finger lever 46 projects from a slot 69 in the box-like portion 35 and is pivoted one way to release the end cover member 24, and in the opposite direction to latch the end cover member 24; but the cover cannot be latched until both sides of the cover have been pressed down firmly, until both of the plungers 57, 58 register with the apertures in the keeper plates 67, 68, thereby insuring uniform pressure on the feed rollers at both ends of the feed rollers.

The bearing blocks 59 and 60 are secured to the top flange 70 of an angle member having a vertical flange 71 welded to the inside of the vertical wall 39 of the box-like formation 35 so that top flange 70 resiliently supports the bearing blocks 59 and 60, urging the bearing blocks 59 and 60 and the feed roller 72 carried by cover member 24 or 24a toward the lower feed roller 73.

The upper feed roller 72 preferably comprises a cylindrical shaft 74 rotatably mounted in bearings 75, 76 in the bearing blocks 59 and 60. The upper feed roller 72 preferably carries a pair of feed discs 77, 78, the radius of which is such that the edges 79 and 80 of these discs engage the edges 81, 82 of the feed discs 83, 84 carried by the lower roller 73.

The lower feed discs 83, 84 are of minimum radius so that the lower roller 73 may serve as a tear-off surface against which the lower tickets may be torn off in Fig. 4.

One type of ticket used with the present register is shown in dotted lines in Fig. 1 and indicated by the numeral 85. This type of ticket has punched holes 86, 87, which are large enough to prevent the feed discs 77, 78, 83, 84 from engaging any part of the ticket, the discs engaging each other when the ticket reaches this point, this being the point at which its major portion is in registry with the window 38.

At this point the discs no longer feed the paper tickets;

but the cams, indicated at 88, 89, come into engagement with the paper tickets adjacent their outer edges, where there are no holes, when the cams are in the position of Fig. 11. There are two pairs of these cams, shown on the shaft 72, and indicated at 88 and 89 in each case.

The cams are pressed toward each other by the resilient action of the angle flange 70, on which the bearing blocks 59 and 60 are mounted.

At its right end shaft 72 carries a gear or pinion 90 meshing with a second pinion 91 on shaft 73. At its left end shaft 72 carries a ratchet wheel 92 having a single V shaped notch 93 for engagement with the V shaped end 94 of a pivoted pawl 95.

Pawl 95 has a bellcrank arm 96 and is urged into the notch 93 by a tension coil spring 97 hooked in the arm and urging the pawl toward the notch.

The arm 96 is located to engage the top edge 98 of the side wall 22 when the cover is closed, so that the pawl 95 is automatically released when the cover is closed and the gears are meshed.

The lower shaft 73 has its cylindrical end portions 99 and 100 rotatably mounted in bearings formed in bearing plates 101 and 102 carried by the side walls. The pinion carried by lower shaft 73 is wide enough in an axial direction to engage not only the teeth on the pinion 90 of the other roller, but it also engages the inside teeth 103 of an internal gear 104, which may be made of plastic or die cast, being provided with an integral crank 105 and shaft 106.

The crank arm 107 is provided with a rotatably mounted handle 108; and the shaft 106 is rotatably mounted in a bearing 109 carried by the side wall 23. The shaft 106 has a thrust bearing 110 at its outer end and is provided with a washer 111 engaging the end of the bearing 109 and with a retaining spring 112 located in a groove 113 in the end of the shaft.

The internal gear 104 also acts as a cover for the gear teeth 103; and the pinion 91 and the number of teeth in these gears are so related that a single turn of the crank arm 105 is sufficient to move a ticket over its full length from one position to the next position, the tickets being attached to each other and separated by lines of perforations.

In order to stop the ticket in the proper position when the cams are ready to take over further movement of the ticket, the side wall 23 is provided with a spring pressed plunger 114 adapted to project into the path of the crank arm 105, as shown in Fig. 7.

This plunger 114 is slidably mounted in a cylindrical housing 115, the end of which may be reduced at 116 and secured in the side wall 23. The housing 115 has a cylindrical bore 117 containing a compression coil spring 118 seated against the riveted-over end 119 of the housing and engaging a collar 120 on plunger 114.

The cylindrical end 121 of plunger 114 slides in bore 122 and is constantly pressed outward to be located in the path of the crank arm 105; but the plunger may be pressed backward into its housing to permit the crank to pass it; and this is done with the thumb or other finger before rotating the crank once.

The teeth of pinion 91 are meshed with teeth 103 of the internal gear at such a point that the cams engage each other when the handle is at the end of its movement, engaging stop plunger 114. At this time the feed discs are also engaging each other, but engage each other through the holes 86, 87 in the paper tickets so that they no longer drive the ticket, which comes to a standstill.

Since the cover 24 may be lifted with the shaft 72 and gear 90, provision has been made to set this gear in proper position to be timed with respect to gear 91 on the lower roller. This is accomplished by means of the pawl 95, which engages in the V groove 93 when the upper shaft has been turned by hand into this position.

If the handle 105 of the crank is in its lowermost position, engaging the plunger 114 when the pawl 95 is in the

groove 93, then the teeth of pinion 90 and teeth of pinion 91 will mesh properly for timed operation of the upper and lower rollers.

Suitable instructions are to be placed in the cover for the user to move the handle 105 and the shaft 72 to the proper position for meshing of the gears before closing the cover.

The pawl 95 rides on the periphery of the ratchet wheel 92, which has only one groove, when the gear teeth are not in the proper position; and the pawl 95 snaps into the groove 93 when the gear teeth assume the proper position. The closure of the cover removes the pawl 95 from the groove, permitting the shaft 72 to rotate freely.

The two covers 24 and 25 may be provided with inwardly projecting flanges 125, 126, 127, and 128, overlapping outside each of the side walls 22 and 23 to effect a complete closure of the housing and a finished appearance.

A bearing plate 129 may be secured to the side housing 23 by the screw bolts 130 (Fig. 2); and the bearing plate has a peripheral cylindrical flange 131 for housing the gear 91, which is also partly housed by the peripheral flange 132 on the internal gear 104, which latter flange supports the internal teeth 103.

The housing preferably has a central partition 133 supported by an angular attaching flange 134, which is welded to the bottom; and the partition separates the two stacks 135 and 136 of tickets.

In the embodiment of Fig. 3, which has the bottom-filed tickets, the partition 133 extends up to a point near the top of the casing.

In the embodiment of Fig. 4, the partition 133a extends up to the guide housing 137, which comprises a box-like member registering with two side apertures 138 in the housing walls 22 and 23. In Fig. 4 the box-like guide 137 comprises a plane bottom 139, a right angular end flange 140, and a curved guide flange 141. This guide member 137 is attached to the side walls by downwardly turned attaching flanges 142.

The curved guide member 141 extends up high enough to overlap another curved guide flange 143 (Fig. 8) on a pivoted guide member 144.

In order to support the paper of the tickets for writing, there is a table member 145 located beneath the window 38 and extending from side to side of the top of the housing inside the side walls 22 and 23. This table member 145 has downwardly turned side flanges 146 fitting inside the side walls 22 and 23 and bolted to the side walls by screw bolts.

The table member 145 has a horizontal portion 147 under the window, but it is turned diagonally downward at 148 and has an upwardly sloping portion 149 at the end, where it receives new tickets. The sloping portion 149 has a curved supporting flange 150 welded to a transverse bolt or rod 151, which is secured in the side walls 22 and 23 by welding or riveting.

The side walls of the housing extend upwardly at 152 above the sloping portion 149 of the table and have an open groove 153 which leads to a forwardly extending slot 154 for supporting the carbons or other reproducing medium in the form of a sheet 155 supported by a transverse cardboard 156, which has its ends mounted in the slot 154.

The sheets 155 may be successive carbons or other reproducing medium, such as sheets supporting a chemical which makes marks under pressure when engaged by another chemical coating on the bottom of the tickets. Carbons or sheets supporting chemical coatings may be used for making copies, or these reproducing sheets may be eliminated when the tickets themselves have bottom and top coatings that reproduce markings on second sheets under pressure of a pencil or stylus.

The box-like guide 137 extends from side to side of the housing at the two holes 138; and in order to permit the fingers to get under and over a ticket in this box-like guide 137, there is a metal strap 157 secured by an attaching

flange 158 to the end wall 140 and extending diagonally to the point 159, where it is welded to the bottom 139, guiding a ticket 160 upward on the floor or bottom 139 of the housing. The strap 157 may be only an inch wide, thereby exposing most of the bottom of the ticket edgewise at either hole 138.

The housing is provided with one of the two pivoted guide members shown at 144 (Fig. 8) and 161 (Fig. 9), depending on the question whether it is the top ticket to be filed or the bottom tickets to be filed.

In the embodiment of Fig. 3 the top ticket 162 is guided out of the aperture 163 below the box-like housing 35; but the bottom tickets 164 (Fig. 3) are directed downwardly by a curved guide flange 165 carried by the wall 31 of cover 25.

In this embodiment of the invention the pivoted guide 161 of Fig. 9 is employed and arranged as follows. This guide comprises a thin sheet metal member having a curled flange 166 arranged about a pin 167, which extends from end to end and has its ends pivoted in apertures 168 in the side walls.

This pivoted guide 161 extends rearwardly from its pin 167 and has its flange provided with tapered cut-outs 169, 170 near its ends for accommodating the feed discs 25 77, 78 and permitting them to engage the paper.

The pivoted guide has corner cut-outs 171, 172 at its ends for accommodating the feeding cams 88 and permitting them to engage the paper; but the main body of the flange of the pivoted guide 161 is adapted to be located in overlapping relation with the set of tickets under the first ticket and over the second two tickets so that the first ticket may be guided upward and the other two tickets downward in Fig. 3.

The guide is pivoted so that it may be directed upward 35 when tickets are being placed on the table; and the cut-out portions also permit the large apertures 86, 87 of the ticket assembly to be located directly over the lower discs 83, 84 so that the tickets will be in proper relation to the rollers when first installed.

In the embodiment of Fig. 4 a different type of pivoted 40 guide 144 is employed. This guide has the same pivot pin 167 located in the curled portion 166 of the guide 144, and the ends of the pin are pivoted in the side wall apertures, as previously described.

The guide 144 has a lower curved flange 143 welded to its body for use in directing tickets downwardly from the rollers into the box-like member 137, as shown in Fig. 4. The guide 144 has the same end cut-outs 171, 172 for exposing the cams to the paper. It has the same tapered cut-outs 169, 170 for exposing the paper to the feed discs 50 77, 78.

It is so arranged with respect to the papers of the tickets that the uppermost ticket goes over the top of the guide 144 and is directed by a rearwardly extending tongue 55 173 under the cover 25a, where it is turned downwardly by the curved guide flange 165 that directs the tickets to be folded in the stack 135.

Thus the top and original ticket is preserved in Fig. 4. One or more lower tickets are located under the pivoted 60 guide 144 at their leading edge and are, therefore, directed downwardly by the curved flange 143 and the curved flange 141 of the side open box 137, where these tickets are located on the strap 157 and indicated at 160 in Fig. 4.

The lower tickets may then be grasped by the hand, reaching into either side of the openings 138, and torn off against the lower roller 73 at the approximate point 174, where the perforations will be located. No other tear-off edge need be provided, as the tickets tear off perfectly against the lower roller 73.

The internal gear 104 is provided with a pawl 175 (Fig. 70 13) pivoted on a screw bolt 176 and spring pressed by a spring 177 against the internal teeth 103, permitting this gear to rotate only in one direction, which is the direction that feeds the tickets forwardly.

The operation of the embodiment shown in Figs. 2 and

3 is as follows: The first and second and the third tickets may be arranged in a stack 136 in which the rear of the front ticket and the rear of each succeeding ticket has a chemical coating that combines with the chemical coating on the front of the next ticket upon pressure contact with a pencil to make a record, in which case no carbons are required.

In other types of tickets not so coated with chemicals carbon sheets may be employed between the tickets on the table 145, or sheets which are coated above and below with suitable chemical coatings may be used in the place of carbons to make copies.

The sets of tickets with suitable reproducing means are secured end to end, divided by perforations and provided with the holes 86, 87, so that the tickets feed continuously from the stack 136 over the curved end 150 and upward over the top of the table 145 to the rollers 72, 73, where the tickets are located in synchronism with the discs and cams.

The first set of tickets has its holes 86, 87 located directly over the lower discs 83, 84. The handle is turned to its lowermost stop position against the pin 114; and the upper roller is turned to such position that the pawl 95 is located in the groove 93.

The cover is then moved downward to closed position; and both sides of the cover are pressed downward until the lever 46 (Fig. 12) may be moved into the latching position shown in this figure. When the cover is closed, the tail 96 of pawl 95 engages the upper edge of the housing wall 22 and withdraws the pawl 95 from the groove 93, freeing the upper roller 72.

The upper roller has been held in fixed position only until its gear 90 becomes properly meshed with gear 91.

When it is desired to use the register, the ticket, which is currently exposed through window 38, may be made the subject of the desired record; and when finished, the plunger 114 is pressed inward with the forefinger until the crank 105 will pass the plunger; and the crank 105 is then given one full turn until it again engages the plunger 114.

At the beginning of this motion the discs 77, 78, 83, 84 cannot drive the tickets because the discs do not engage the paper, but engage each other through the holes 86, 87. However, the cams 88, 89 are engaging the tickets above and below; and the cams start to drive the tickets forwardly over their full length until the discs again reach the holes 86, 87 and engage each other without driving the tickets any further.

The tickets have now progressed over one full length of ticket; and in Fig. 3 the top ticket is exposed at 162 to be torn off at its perforations, while being held by the cams 88, 89. The lower tickets have been turned downwardly by the curved guide 165; and due to the folding of the tickets in a continuous stack, the are guided into the stack 135.

In the embodiment of Fig. 4 the operation is the same except the top ticket is directed downwardly into the stack 135, while the lower tickets are directed into the open space 138 in the box-like member 137 to be torn off against the roller 173.

If desired, a suitable roller may be provided adjacent the edge 163 (Fig. 3) against which the upper ticket 162 may be torn off so that the tear-off is located at the same point on the ticket in each type of machine, but I prefer to provide a curved portion 180 on the depending wall 41 of the box-like housing 35, against which the ticket may be torn cleanly like it is torn on the roller 73 in Fig. 4.

There is a great advantage in storing the top ticket because no one can tell whether there has been a mishap in the making of a recording on lower tickets. When the top ticket is given away in the machine of Figs. 2 and 3, a failure of the feed in the lower tickets could possibly occur; and the user could operate until there were no more top tickets, only to find that there had

been a recording only on the top ticket; and the top tickets have been given away, leaving no record of an entire day's sales or of an amount of sales equivalent to the stack of top tickets that have been given away.

5 Where the bottom tickets are given away, as shown in Fig. 4, and the top ticket is stored, the best record is kept; and every time a ticket is made out the copies can be observed before they are given away to make sure that a proper record is being made and preserved in the form of the top ticket.

10 It will thus be observed that I have invented improved forms of autographic registers which may be adapted to dispense the top ticket and preserve lower tickets, or with slight modification may be adapted to dispense lower tickets and preserve the top ticket.

15 The construction of the present machine is simple and still takes the threading or loading of the tickets with the greatest of ease, since the top roller is lifted with the cover to expose the tickets.

20 Provision is made for placing the rollers in proper position for synchronism of the cams and discs with the tickets; and the upper roller is held in proper position by a pawl and ratchet groove until the cover is closed, which automatically withdraws the pawl.

25 The tear-off can be made directly against the lower roller, without any special tear-off edge; and resilient pressure between the feed discs and holding cams is assured by resilient mounting of the bearing blocks for the upper roller.

30 The latching mechanism for the cover cannot be latched until both sides are fully closed; and this assures the same pressure on both sets of cams.

35 While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as 40 new and desire to secure by Letters Patent of the United States is:

1. A register comprising a housing of substantially rectangular shape, having a storage space for unused tickets at one end and another storage space for used tickets at the other end, the said housing having an open top, closed by two covers pivoted on the ends of the housing, one of said covers having a rectangular window opening exposing one of a continuous series of perforated and punched tickets; a table member carried by the housing below said window to provide a backing for the act of writing on said tickets, said tickets being arranged in sets with a suitable reproducing medium for making records on the lower tickets, a first feed roller rotatably mounted on the side walls of the housing and a second feed roller rotatably mounted on one of said covers, the feed rollers being separable for placement of tickets in the machine, meshing gears carried by the rollers for synchronized drive, and means connected to the rollers to place the rollers in proper rotative position for remeshing of the gears after separation by lifting the cover to place the tickets.

2. A register according to claim 1, in which the lower roller is driven by an internally toothed gear provided with a crank and rotatably mounted on the side wall 65 of the housing, one rotation of the latter gear causing the rollers to progress sufficiently to move a new ticket assembly into place.

3. A register according to claim 1, in which the upper roller is provided at its end with a spring pressed pawl and a retaining cam having a V-shaped notch for receiving the pawl and holding the gears in remeshing position.

4. A register according to claim 1, in which the cover carrying the roller is provided with a latching mechanism 75 engaging the housing at each side and actuated by a single

lever so that the cover cannot be latched until both sides are moved into the closed position.

5. A register according to claim 1, in which said second feed roller is rotatably mounted in bearing blocks carried by the said cover on which it is mounted, said latter cover having an angle member with one flange welded to said latter cover and the other flange resiliently supporting said bearing blocks and pressing the second roller against the first roller.

6. A register according to claim 1, in which the housing supports a cylindrical member having a reduced portion mounted in an aperture in the side wall of the housing, said member having a bore containing a helical coil spring and a cylindrical plunger having a collar engaged by the spring and urging the plunger outward into the path of a crank for driving the rollers, the plunger being pressed in by a finger before rotating the crank one turn.

7. A register according to claim 2, in which the internal gear houses a pawl pivotally mounted on the housing, and having its end spring pressed into engagement with the internal teeth so that the internal gear can rotate only in one direction.

8. A register according to claim 1, in which the side walls support a guide plate pivoted on a transverse pin

10

5 mounted in apertures in the side walls and located at the discharge end of the rollers and extending between the rollers, but having cut-outs at its leading edge, permitting the feed rollers to engage the tickets at the cut-outs, said 10 guide plate directing the upper and lower tickets above and below said guide plate.

9. A register according to claim 8, in which the said guide plate directs the top ticket out of an aperture in the cover, while the lower tickets are directed downwardly and deposited inside the housing.

10. A register according to claim 8, in which the guide plate has a rearwardly extending tongue directing the uppermost ticket over the guide plate and under the cover, where it is turned down by a curved guide flange and folded in a stack, while the lower tickets are directed downwardly below the guide plate and backwardly by another curved flange and exposed on a strip in a side open box to be torn off against the lower roller.
